UNITED STATES PATENT OFFICE.

ANDREW W. BRITTER, OF ABILENE, TEXAS.

QUILTING-MACHINE.

995,320.

Specification of Letters Patent. Patented June 13, 1911.

Application filed July 21, 1910. Serial No. 572,971.

To all whom it may concern:

Be it known that I, ANDREW W. BRITTER, a citizen of the United States, residing at Abilene, in the county of Taylor and State 5 of Texas, have invented certain new and useful Improvements in Quilting-Machines, of which the following is a specification.

My invention relates to new and useful improvements in quilting machines. Its object is to provide a machine equipped with 10 a plurality of vertically reciprocating needles and horizontally reciprocating shuttles in conjunction with a take up and a feed mechanism adapted to stitch said quilt by feeding the same once through the machine.

A further object is to provide novel and efficient mechanisms for operating the needles, shuttles, take up and feed.

Finally the object of the invention is to 20 provide a device of the character described that will be strong and durable and comparatively simple in construction, and one, the various parts of which, will not be likely to get out of working order.

With these and various other objects in 25 view, my invention has relation to certain novel features of operation and construction an example of which is described in the following specification and illustrated in the 30 accompanying drawing, wherein:

Figure 1 is a plan view of the quilting machine. Fig. 2 is a front view thereof. Fig. 3 is a vertical sectional view taken on the line X—X of Fig. 1. Fig. 4 is a vertical sectional view taken on the line y—y 35 of Fig. 2. Fig. 5 is an end view of the machine, the main driving shaft and its supporting brackets being broken away.

Referring now more particularly to the 40 drawing, wherein like numerals of reference designate similar parts in all the figures, the numeral 1 denotes the feed table upon which the quilt will be fed to the machine. Beneath this table and spaced therefrom is positioned a bed-plate 2 upon which 45 operate the reciprocating shuttles. Above the table 1 are provided two shelves 3 and 4 spaced from said table and from each other and supported at each end by vertical walls 5. A plurality of rods 6, adapted to undergo a vertical reciprocating motion are mounted in the shelves 3 and 4, said rods being equidistant and horizontally alined. Each of these rods carries an eye-pointed 50 needle 7 upon its lower extremity, and an aperture 8 through which said needle is

adapted to pass is positioned in the work table 1 directly beneath each needle. The rods 6 are rigidly connected by a clamping bar 9 causing them to reciprocate in unison. 60 Each of the two outside rods is acted upon by a connecting rod 10, and the connecting rods are each operated by an eccentric 11 mounted upon the shaft 12. The extremities of this shaft are supported in brackets 65 13 mounted upon the upper shelf 4. A thread 14 passes through the eye of each needle each thread being wound upon a spool 15 mounted upon a pin 16 projecting vertically from the shelf 4. Each thread 70 passes around a pair of tension disks 17 which regulate the strain upon the thread as it is gradually drawn off of the spool through the operation of the needles. The take up consists of a plurality of hooks 18 75 through each of which one of the threads 14 is passed, said hooks being mounted upon an oscillating bar 19. This bar is supported at each extremity by levers 20 mounted upon pivots 21. The inner extremities of 80 each of these levers carries a pin 22 to which an oscillating motion is communicated by a cam 23 provided with a groove 24 in which said pin works. The cams 23 are each mounted upon a shaft 25 from one of 85 which shafts rotation is communicated to the eccentric shaft 12 by a pair of pulleys 26 and a belt 27.

A frame is provided to receive the fabric to be sewed, consisting of a pair of bars 28 90 slidably mounted in grooves in the table 1, and provided with upturned arms 29. At each end of this frame two rods 30 and 31 are mounted in the arms 29 and upon each of the upper rods 31 is mounted a ratchet wheel 95 32 acted upon by a spring pawl 33. The extremities of the fabric are wound upon the rods 31 after having been passed under the rods 30 in order to cause the fabric to lie flat upon the table. A pawl and ratchet 100 mechanism prevents reverse rotation of the rollers which carry the extremities of the cloth so that the fabric is stretched tight while being sewed. A shuttle 34 mounted in a carriage 35 is adapted to reciprocate upon the bed-plate 2 beneath each of the apertures 8, said shuttle having a stroke of sufficient length to carry it from one side of the aperture to the other. Each of the carriages 35 is rigidly connected by a rod 36 with a transverse bar 37, and a reciprocating motion is 105 imparted to said bar through a pair of con-

necting rods 38 and eccentrics 39. The eccentrics are mounted upon a shaft 40 supported at its extremities in brackets 41. The shaft 40 serves as a driving shaft for the 5 other mechanisms of the machine, a pulley 42 being mounted upon said shaft through which rotation may be communicated thereto.

The cam shafts 25 are operated from the 10 shaft 40 through pulleys 43 and belts 44. The fabric being sewed receives its feed motion after each stitch from a number of feed plates 45, one of which is mounted in the surface of the table 1 adjacent to each 15 of the needles. These feed plates are carried upon the upper extremities of arms 46 rigidly secured to oscillating levers 47. One extremity of each of these levers is connected with an eccentric 48 carried by a shaft 20 49, and the other extremity of each lever is provided with a slot 50 receiving a stationary rod 51. Rotation is communicated to the shaft 49 from the shaft 40 through a pair of pulleys 52 and a belt 53. Upon each 25 of the feed plates 45 there rests a bifurcated foot 54 carried in the usual manner at the lower extremity of a rod 55, to which a downward pressure is communicated by a spring 56. The feet 54 serve to hold the 30 fabric securely down upon the work table and upon the feed plates 45. The feed plates are provided with serrated surfaces in order that the cloth will be carried forward by the forward motion of the plate but 35 will not be affected by the rearward motion of said plate. The shuttles employed may be of any suitable and well known construction.

It is obvious that any number of needles may be used to give the required number of 40 stitches.

What I claim is:

In a quilting machine, the combination with a table containing a plurality of aligned apertures, of a vertically reciprocating eye-pointed needle mounted above each aperture, means establishing a rigid connection between all of the needles, eccentrics by which a reciprocating motion is imparted to the gang of needles, a horizontal reciprocating shuttle mounted beneath each of said 45 apertures in the table, eccentrics by which a reciprocating motion is communicated to the shuttle, a serrated feed plate adjacent to each needle, an upright arm carrying each of said feed plates on its upper extremity, an 50 oscillating bar upon which each of the arms is rigidly mounted, a spring pressed bifurcated foot resting upon each of said feed plates, a grooved cam mounted at each extremity of the quilting machine, a pair of 55 pivotally mounted levers, one of the extremities of each of which is adapted to be transversely oscillated by one of said cams, a bar connecting each of the two extremities of the levers, and means carried by said bar engaging each of the threads, passing through 60 said needles.

In testimony whereof I have signed my name to this specification in the presence of two subscribing witnesses.

ANDREW W. BRITTER.
